UNITED STATES PATENT OFFICE.

CHARLES I. STOLOFF, OF NEW YORK, N. Y.

ART OF DENTAL PROSTHETICS.

Application filed January 12, 1924. Serial No. 685,823.

My invention relates to new and useful improvements in artificial plate and bridge dentures, and more particularly to a new type of attachment construction therefor.

It has been the primary purpose of the invention to provide a locking hinge attachment, whereby there has been effected a multi-sectioned plate denture formation, i. e., an arrangement formed of a main plate and one or more auxiliary plate denture sections, each section being joined to the main plate denture through the medium of this attachment. In plate denture work, in the case of metallic and rubber plates, where it is the aim to provide as much retentional contact between the plate and gum as possible, it often necessitates cutting down gum protuberances and under-cuts, or, on the other hand, causing the user inconvenience and pain when removing from or replacing the plate in the mouth. However, by the provision of this sectional plate arrangement, these very gum protuberances and under-cuts can be adapted, in cooperation with the auxiliary sections of the plate, to be used as additional retaining and supporting means against unintentional dislodgement of the plate from the mouth, without resulting in the inconvenience and pain when removing or replacing the plate. Furthermore, it is particularly intended that the gripping area of this multi-sectioned plate be extended, so that the mylohyoid ridge can be utilized as a co-operating local for positioning auxiliary plate sections.

Another object of this invention has been to provide a locking means for the hinge attachment that is positive in its operation, readily accessible, and forming with the hinge member a compact arrangement.

With the preceding and further objects and advantages obvious and manifested hereinafter, the invention consists of the novel features, the application and arrangement of the parts more specifically described in the specification following, and illustrated in the accompanying drawing.

A preferred and practical embodiment of my invention is shown in the accompanying drawing, in which like reference characters indicate the corresponding parts throughout the different views.

In the accompanying drawing:

Figure 1 is a perspective view of each part of the attachment, collectively grouped.

Fig. 2 is a lateral section through the cen-

ter of the attachment, showing a fragmentary view of the rubber plate sections.

Fig. 3 is an elevation of a half section of jaw with a fragmentary elevation of a rubber plate, showing the attachment in position.

The attachment forming the substance of this invention consists of a locking hinge arrangement, a simple form being shown in the various views of the drawing. Here, referring particularly to Figures 1 and 2, the main hinging elements of the attachment are indicated by the parts 1 and 2. Arbitrarily, the hinge element 1 is shown of H form, and the hinge element 2 of inverted T form. Through the lower pair of uprights of the element 1 are positioned, laterally, aligning bearing holes 3, and through the upright leg of the element 2 is positioned, correspondingly, a similar bearing hole 3, so that, when the leg of the element 2 is interposed between the lower set of uprights of the element 1 and a shaft pin 4 made to journal within the three bearing holes 3, a hinging connection will exist between the elements 1 and 2.

On the locking element 5 is formed, midway laterally and on line with the top edge, a linking arm 6 to be interposed between the upper uprights of the hinging element 1, referring to Figures 1 and 2. Also, there are positioned aligning bearing holes 7, one through each of the upper uprights, laterally, of the element 1, and a corresponding one through the linking arm 6, so that, when a shaft pin 4 similar to the one mentioned before, is made to journal through this set of bearing holes 7, a hinging connection will likewise exist between the hinging element 1 and the locking element 5.

On the locking element 5 is also formed, midway laterally near the lower edge, an extending pin knob 8, to engage within a cooperatively positioned receptacle 9, i. e., a through hole in the body of the hinging element 2, reference being had to Figures 1 and 2. Thus, when the locking element 5 is swivelled so that the knob 8 is forced into its receptacle 9, the hinging elements 1 and 2 will be held in rigid relationship, i. e., they will be unable to swivel.

A method of application of my principle of plate construction, in an instance of rubber plate work, is illustrated in Fig. 3. Here, a common type of rubber plate 10 is shown in position on the jaw 11, the inside edge

of the plate 10 being assumed to extend downward to meet the mylohyoid ridge 12. The auxiliary rubber plate section 13 would then be formed, closely hugging the surface of the mylohyoid ridge, to extend completely thereabout. The length of upper edge of the auxiliary plate 13, and that length of lower edge of the main plate 10 abutting it, would be formed to make a close fitting joint.

10 In Fig. 3, I illustrate one manner of mounting the attachment, showing its application as the joining medium for the main plate 10 and auxiliary plate 13. In this case the hinging element 1 of the attachment, is embedded in the auxiliary plate section 13, preferably during the vulcanization of the auxiliary plate, proximately to that edge which is to butt against the main plate, and centrally of the width of 20 the auxiliary plate. Similarly, the hinging element 2 would then be embedded, preferably also during the vulcanization of the main plate, in such a position in the main plate 10, and proximately to its edge, that the 25 auxiliary plate 13 and main plate 10 assume a predetermined relative position. Regarding the procedure for the preparation and vulcanization of both the main and auxiliary plates, nothing has been said in the 30 foregoing, it being understood to be carried out in a manner well known to those skilled in the art and technique of this branch of dentistry.

Although I have shown in Fig. 3, the 35 attachment mounted on the plate with the hinging element 1 permanently seated on the auxiliary plate 13, and the hinging element 2 permanently seated on the main plate 10, the reverse of this order of mounting the 40 elements of the attachment may in some instances be preferable, this latter manner of mounting the hinging elements being illustrated in Fig. 2. What should decide the order of mounting is the space available 45 for manipulating the locking element 5 with the finger, which in turn would depend on the particular location of the auxiliary plate section 13.

To seat the plate arrangement in the 50 mouth, it would be simply necessary to disengage the locking element so that the knob extension 8 is free of its receptacle 9, insert the plate in the mouth in the ordinary manner, then with the finger snap the locking 55 element against the hinging element 2, forcing the knob extension 8 into its receptacle 9. The hinging elements 1 and 2 now held in fixed relationship to each other, will cause a rigid relationship to exist between 60 the auxiliary plate 13 and the main plate 10, i. e., as if the main and auxiliary plates were of solid section. To remove the plate arrangement from the mouth, the locking element 5 is slightly lifted with the finger, 65 disengaging the knob extension from its re-

ceptacle, and the plate will be readily removable.

In the accompanying drawing I have illustrated my principle of plate construction, in a case showing but a single auxiliary plate section 13. This has been done for simplicity, the proper number of auxiliary plate sections to be employed with a main plate being generally more than one, the decision being governed by the conditions existing in the mouth of the patient.

This principle of plate construction, I particularly wish to set forth, can be very readily applied to ordinary plates already existent and in use in the mouth. It would only be necessary to vulcanize a proper form of auxiliary plate section, and join it to the already existing plate through the medium of the attachment. Also, this principle of plate construction is just as readily adaptable to all types of metallic plate work, such as gold plates and the like, the auxiliary plate sections being joined to the main plate through the medium of the attachment, the hinging elements of the attachment being mounted (soldered preferably) onto the respective metallic plate sections, in a similar manner as described and illustrated in the foregoing.

It is obvious, that this invention, a practical embodiment of which has been hereinbefore described and illustrated, is not necessarily limited to the character of denture specifically set forth in the foregoing, but can be modified to be applicable to different types and classes of artificial dentures; and is moreover not limited to those details of construction which have been more particularly described, changes thereof being readily resorted to, within scope and spirit of the appended claims.

What I claim is:

1. A multi-sectional denture formation comprising an artificial main plate denture section and an artificial auxiliary plate denture section movably joined thereto, the adjoining walls of the main and auxiliary plate sections being arranged in abutting relation.

2. A multi-sectional denture formation comprising a main plate denture section adapted to seat on the jaw and an auxiliary terminal plate section adapted to seat in the retro-alveolar region, the said terminal plate section being movably joined to the main plate section for facilitating lodgement of the denture formation within and dislodgement of the same from the mouth, the adjoining walls of the main and terminal plate sections being arranged in abutting close fitting relation.

3. An artificial multi-sectional denture formation comprising a main plate denture section and an auxiliary plate denture section, the adjoining walls of the main and

auxiliary plate sections being arranged in abutting relation, and a connecting structure joining the auxiliary plate section to the main plate section for movement relatively 5 to the latter.

4. A multi-sectional denture formation comprising an artificial main plate denture section and an artificial auxiliary plate denture section, and a connecting structure joining the auxiliary plate section to the main plate section for movement relatively to the latter, the said connecting structure including means for locking the sections together in fixed position.

15 5. A multi-sectional denture formation comprising an artificial main plate denture section adapted to seat on the jaw, an artificial auxiliary terminal plate section adapted to seat in the retro-alveolar region, and a connecting structure joining the terminal plate section to the main plate section for movement relatively thereto for facilitating lodgement of the denture formation within and dislodgement 20 of the same from the mouth, the adjoining walls of the main and auxiliary plate sections being arranged in abutting relation.

6. A multi-sectional denture formation comprising a main plate denture section 30 adapted to seat on the jaw, an auxiliary terminal plate section adapted to seat in the retro-alveolar region, and a connecting structure joining the terminal plate section to the main plate section for movement relatively thereto for facilitating lodgement of the denture formation within and dislodgement 35 of the same from the mouth, the said

connecting structure including means for locking the sections together in fixed position.

7. A multi-sectional denture formation comprising an artificial main plate denture section and an artificial auxiliary plate denture section, the adjoining walls of the main and auxiliary plate sections being arranged in abutting close fitting relation, and a hinge structure pivotally joining the auxiliary section to the main plate section.

8. A joining structure for artificial dentures of the character described, comprising a hinging element adapted to be permanently mounted on a main plate section, a second hinging element adapted to be permanently mounted on an auxiliary plate denture, a locking element hingedly mounted upon one of the said hinging elements, the said locking elements having formed thereon an extending pin knob adapted to engage within a corresponding receptacle co-operatively positioned on the other of said hinging elements, and a shaft pin for joining the aforementioned respective hinging and locking elements.

9. A joining structure for artificial dentures of the character described, comprising a hinging element adapted to be permanently mounted on a main plate denture, a second and complementary hinging element adapted to be permanently mounted on an auxiliary plate denture, and a locking element hingedly mounted upon one of the said hinging elements and having locking means for engaging the other of the hinging elements.

CHARLES I. STOLOFF, D. D. S.
